UNITED STATES PATENT OFFICE.

RAYMOND A. HEISING, OF EAST ORANGE, NEW JERSEY, ASSIGNOR TO WESTERN ELECTRIC COMPANY, INCORPORATED, OF NEW YORK, N. Y., A CORPORATION OF NEW YORK.

MODULATING AND TRANSMITTING SYSTEM.

Application filed April 13, 1918. Serial No. 228,416.

To all whom it may concern:

Be it known that I, RAYMOND A. HEISING, a citizen of the United States, residing at East Orange, in the county of Essex and 5 State of New Jersey, have invented certain new and useful Improvements in Modulating and Transmitting Systems, of which the following is a full, clear, concise, and exact description.

10 This invention relates to means for generating, modulating and transmitting electrical oscillations, and more particularly to generating oscillations by means of electrical discharge devices.

15 An object of the invention is to effect an improvement in the manner in which electrical discharge devices may be associated in signaling and other systems.

Another object is to provide a system in 20 which a plurality of electrical discharge devices are associated with suitable circuits to act as oscillation generating means.

Further objects are to produce a signaling 25 system with which modulated and unmodulated signals may be sent, and in which a vacuum tube oscillates directly into an antenna.

The invention is exemplified herein in a 30 radio signal transmitting system wherein the antenna itself is included in and forms a frequency-determining element of a high-frequency oscillating circuit, and is directly associated with a vacuum tube oscillator or a series of vacuum tubes acting as an oscillator. The oscillation frequency is determined by the circuit which includes the antenna. Vacuum tubes for modulating have 35 been provided to effect the signaling modulation of the oscillations to be transmitted.

40 In the accompanying drawings Fig. 1 represents diagrammatically a form of the invention adapted to be used as a radio telephone transmitting station; Fig. 2 is a modified form of that part of Fig. 1 to the right 45 of the line X—X; and Fig. 3 is a circuit arrangement adapted for telegraphy.

The general organization as shown in Fig. 1 includes an oscillator and a modulator therefor which is controlled by a microphone. In detail, the antenna circuit 1 consists of the aerial 2, inductance coil 3, condenser 4, which is connected to ground at G. Adjustment of condenser 4 causes the alternating voltage impressed upon the grid to

be varied. Coil 3 has an adjustable connection to the plate of the oscillating tube O through conductor 5. Conductor 6 connects the lower end of coil 3 to the grid of tube O through stopping condenser 7. Conductor 6 may be adjustably connected to coil 3, as 60 shown in dotted lines, if it is desired to use this means of regulating the feed-back coupling of the oscillator instead of varying condenser 4. Leak resistance 8 of a large numerical value, is provided to allow an excess 65 negative charge to leak from the grid of tube O, and resistance 9 is adjustably connected to resistance 8 and to the grid of tube M through conductor 10, for applying a suitable average value of negative potential 70 to the grid of the tube M. The source of electrical energy E_p, which may be any suitable source and is here represented as a battery, furnishes plate-filament current for 75 both the tubes O and M which passes through the large choke coil 11 having an iron core. Coil 11 tends to keep the current through itself constant and thus any variation of internal impedance of the tube M affects the potential between the anode and 80 cathode of the tube O. The connection from coil 11 to the plate of tube O includes high frequency choke coil 12, conductor 13, coil 3 and conductor 5. Since coil 11 consists of 85 many turns it will have considerable capacity reactance at high frequencies, which would tend to act as a shunt upon the capacity 4, and the function of the coil 12 is to make inductive reactance predominate 90 and prevent short-circuiting of condenser 4. The coil 12 is a radio frequency induction 95 coil and necessarily has small distributed capacity in order to make inductive reactance predominate in the circuit at high frequencies. It is well known that such coils may be constructed of a single layer of spaced turns, but other constructions may be used. Battery E_t heats the filamentary 100 cathodes of both tubes, being connected to conductors 14 and 15, while the conductor 16 grounds the negative terminals of both batteries. Microphone 17 is connected to the tube M through transformer 18 whose secondary is connected across the resistance 19, one end of which is connected to the grid 105 or control electrode of the modulator M, and the other to the filament or cathode through conductor 10, capacity 20 and conductors 21

and 15. The capacity 20 is of low impedance to speech frequency currents as compared with the grid-to-filament impedance of the tube M. The input circuit of the tube M 5 may be considered as including the arrangement constituting the capacity 20 in parallel with the resistance 9 and a part of resistance 8. This arrangement avoids the necessity of providing a grid battery for the tube M.

10 In operation, variations of potential of sound or speech frequency are impressed upon the grid of tube M which cause variations in its internal impedance. As coil 11 tends to maintain constant current through 15 itself, there will be variations of anode-cathode potential across the continuously oscillating tube O, which will cause its oscillations to be modulated in amplitude in accordance with the fluctuating potentials induced by microphone 17.

The arrangement of Fig. 2 may be substituted for that part of Fig. 1 which lies to the right of the line X—X and is designed to prevent the positive terminal of 25 the battery E_p from being directly connected to the antenna. This is accomplished by having conductor 13 connected to conductor 5 instead of to conductor 6, as in Fig. 1. A capacity 22 is then placed between the 30 junction point of conductors 5 and 13 and the coil 3. With this arrangement, accidental grounding of the antenna 2, such as might occur if this system is used on aeroplanes or boats, would not short-circuit 35 the battery E_p . This arrangement has the additional important advantage that the electromotive force of speech frequency which is impressed across the anode-cathode terminals of the tube O is not materially 40 shunted through the circuit comprising capacity 22, coil 3 and capacity 4, since two small condensers (as regards speech frequencies) are included therein. This prevents waste of energy and also causes the 45 impedance offered by the circuit comprising elements 22, 3 and 4 to high speech frequencies to be almost the same as to low speech frequencies. This circumstance causes the impedance across the anode-cathode 50 terminals of the oscillator to be substantially the same for the entire range of speech frequencies and therefore produces better modulation. In the case where the 55 modulating frequency or frequencies impressed upon the generator O are other than speech frequencies, as in Figure 3, the requirements are somewhat similar since, although the modulating wave may consist of a single frequency or a narrow band of 60 frequencies, it may differ from the high frequency by a smaller percentage than in the case of speech modulation.

The transmitting system shown in Fig. 3 is intended for transmitting both modulated 65 and unmodulated telegraphic signals, al-

though with suitable modification it could be used for telephony. This arrangement is closely analogous to that of Figs. 1 and 2, and the parts which bear identical reference characters can be identified by referring to the preceding description. A low frequency oscillator O' and a series of modulators M are combined with a series of tubes O which constitute a high frequency oscillating system, the tubes O being arranged in parallel. A filter 23 in the conductor 5 consists of an adjustable capacity and an inductance and is tuned to a frequency approximating that of the low frequency oscillator O' to prevent low frequency oscillations from passing along conductor 13 to the grids of tubes O through the coil 3, capacity 7 and conductor 6. The condenser 22 also aids in preventing such action. The low frequency oscillator O' has 85 an oscillation circuit consisting of variable capacity 24 and inductances 25 and 26. Stopping condenser 27 is also included in the oscillation circuit. Stopping condenser 29 serves to allow alternating current to 90 flow in the grid circuit without passing through any of resistance 28 except the part between the two taps thereon. Resistance 28 forms a grid leak for tube O' and a small variable portion thereof may be placed in 95 the input circuit. Tap 34 provides a source of negative potential for the grids of modulators M. The key K' is arranged to shunt the inductance 26 which changes the frequency of oscillator O'. Oscillations generated by the tube O' cause corresponding changes of potential and of space current across the tubes M which serve to modulate the high frequency oscillations generated by tubes O in the same manner in which the 100 tube M in Fig. 1 operates. It will be noted that the source of current E_p and choke coil 11 are common to the circuit of tubes M and O in both figures. Resistance 30 may be provided to cause tube O' to work 105 at a lower plate-filament potential than tubes M and O. The resistance 30 also serves to stabilize the output of tube O' and to eliminate harmonics.

Referring again to the antenna, the capacity 31 may be in shunt with the aerial capacity and serves as a convenient means of tuning and adjusting the antenna capacity, and hence the frequency. Capacities 31 and 32 are not essential features of the invention and either or both of them may be omitted without rendering the circuit inoperative. Condenser 32 may be omitted, but if present must be of sufficiently large capacity that high frequency will pass therethrough readily. It will prevent either terminal of the battery system from being grounded, in which case an accidental ground on either the aerial or some other part of the system will not short-circuit the 115 120 125 130

battery. This feature is of utility in systems used upon aeroplanes or boats. Condenser 32 also aids the filter 23 in preventing the relatively low frequency electromotive force impressed across the anode-cathode terminals of the tube O from being shunted through or impressed upon the antenna circuit. Capacity 4 consists of adjustable capacity 4^a in series with the large capacity 4^b, which latter is shunted by key K. Suitable switches s may be provided to cut off the current supply from the battery system.

This system is capable of operating in two distinct ways. If the oscillation system O is working at a normal frequency of, for example, 100,000 cycles, and key K is closed, the frequency will change to, for example 99,000 cycles if the adjustments are proper. At a suitable receiving station a local generator having a suitable frequency will give a heterodyne beat note when key K is closed, and a different or inaudible note when key K is open. This action will be independent of the action of tubes O' and M which may meanwhile be left either operative or inoperative.

Suppose, however, the generation system including tubes O is operating at a frequency of 100,000, and generator O' at a frequency of 15,000 cycles. When key K' is closed, the frequency of generator O' will change to, for example, 14,000 cycles. In this case the waves may be received at a receiving station having a detector for deriving the lower frequency from the modulated wave and a suitable heterodyne local source of oscillations of proper frequency.

While certain specific modifications have been illustrated herein and described in detail, the invention is capable of embodiment in various physical forms, and the appended claims are intended to include all equivalent arrangements, or where only a group of elements is defined in the claims, it is intended to include the use of such group in any equivalent system. While radio systems only have been described herein to illustrate the invention, systems employing wires might also have been used as illustrations. Since, under certain circumstances, it may be desirable to modulate oscillations at a receiving station or elsewhere, as well as at a transmitting station, it is not intended to limit this or other features of the invention to use for transmitting.

What is claimed is:

1. In a radio signaling system, an antenna circuit, a vacuum tube, an anode and a conducting element in said tube, means for impressing a low frequency voltage between said anode and said element, a conductor connecting said anode to said antenna circuit, and a plurality of elements constituting a low frequency filter located in said con-

ductor for preventing the flow of current therethrough due to said voltage.

2. In a radio signaling system, an antenna circuit, a discharge tube, an anode therein, a conductor connecting said anode to said antenna circuit, said conductor and a portion of said antenna circuit constituting a shunt path to said tube with respect to a source of modulating waves, and an impedance means located in said conductor constituting a high impedance to relatively low frequencies for preventing current flow due to low frequency voltage changes through said conductor.

3. In a signaling system, a source of low frequency oscillations and a source of high frequency oscillations, said high frequency source including a discharge tube having a control electrode therein, an alternating current conductive path from said low frequency source to said control electrode, and a filter in said path for offering relatively high impedance to oscillations of the approximate frequency generated by said low frequency source.

4. In combination, an oscillation generator, a second oscillation generator, said generators each including a vacuum tube having electrodes therein, alternating current input, output and feed-back circuits for said generators, means whereby the oscillations of the second generator may be modulated in accordance with the oscillations of the first mentioned generator, said means including a plurality of conductive connections between electrodes of different of said tubes.

5. In combination, an oscillation generator, a second oscillation generator, said generators each including a discharge device having a plurality of electrodes, alternating current input, output and feed-back circuits for said generators, and means whereby the oscillations of one of said generators may be modulated in accordance with the oscillations of the other, said means including conductive connections between said electrodes.

6. In combination, an oscillation generator, a second oscillation generator, means whereby the oscillations of the second generator may be modulated in accordance with the oscillations of the first mentioned generator, means whereby the oscillations of one of said generators may be varied to signal, and means whereby the oscillations of the other of said generators may be independently varied to signal.

7. A modulating system comprising a source of electrical waves, means for causing an interaction between the waves from said source and other waves to produce modulated waves, said source and said means each including a space discharge device having a cathode and an impedance varying element, a leak path conductive to direct current extending from one of said cathodes to the corresponding impedance varying element,

- and a tap connection conductive to direct current extending from a point on said path to the impedance varying element of the other said space discharge device.
- 5 8. In a signaling system, a low frequency vacuum tube oscillator associated with a high frequency vacuum tube oscillator, means for varying the frequency of each of said oscillators, means for operatively connecting said 10 oscillators so that a change of frequency of either will have a negligible effect upon the oscillation frequency of the other, and means for causing a characteristic of the oscillations of one of said generators to change in accordance with the oscillations of the other.
9. In combination, a discharge tube, an antenna circuit directly associated with said tube so as to determine the frequency of oscillation thereof, a set of modulating tubes 20 operatively associated with said first mentioned tube, and a control tube operatively associated with said modulating tubes.
10. In a transmitting system, an oscillating means, a modulating means capable of 25 oscillating at two constant frequencies, and means for signaling by intermittently causing said modulating means to oscillate at each of said frequencies.
11. A source of high frequency oscillations, a plurality of space discharge devices 30 associated therewith so that the internal impedance of said devices determines a characteristic of said oscillations, said devices each having an anode, a cathode and a control 35 electrode, said anodes, cathodes and control electrodes being directly connected by conductors of negligible impedance, and a constant current supply for said devices and said source.
- 40 12. A system comprising a space discharge oscillator having a control element and an electrode; a leak path from said element to said electrode, a lead from a point on said path to the control element of an electron 45 discharge device for maintaining a given average working potential on said second-mentioned control element, and a condenser connecting a point in said lead and said electrode.
- 50 13. In an electrical system, a series arrangement of impedance elements adapted to have high impedance at a relatively low range of frequencies and high impedance at a relatively high range of frequencies comprising an inductance coil having a magnetic core for producing the desired high impedance at the low range of frequencies, and an inductance coil in series therewith having sufficiently high impedance at the relatively 55 high range of frequencies to more than counteract the capacity effect of the first named coil at the high range of frequencies and thereby produce the desired high impedance.
- 60 14. In an electrical system, a series arrangement of impedance elements having 65 relatively high impedance at a high range of frequencies and relatively high impedance at a low range of frequencies and being conductive to direct current comprising a choke coil having the desired high impedance at the low range of frequencies but having a capacity effect sufficient to produce a relatively low impedance at the high range of frequencies, and an inductance coil in series therewith having sufficient inductive reactance at the high range of frequencies to produce the desired high impedance.
15. In an electric system, a circuit, an inductive impedance means therein for maintaining a constant direct current in a part of 80 said circuit, said impedance means having a capacity reactance at high frequencies, and an inductance coil in said circuit to counteract said capacity reactance.
16. In combination in a transmitting system, an antenna including an aerial, an inductance and a capacity, a vacuum tube oscillating system connected to said antenna, a cathode, an anode and an impedance-varying element included by said oscillating system, 90 said cathode, anode and impedance-varying element being connected to points of normally different potential in said antenna when the system is operating; a vacuum tube modulating system for said oscillating system, an anode, a cathode and an impedance-varying element in said modulating system, a space current path in said modulating system and a space current path in said oscillating system, said paths being in parallel 100 with respect to a source of electromotive force, a circuit in which said source is located, and means in said circuit for maintaining the sum of the space currents in said paths constant, a second oscillating vacuum tube system associated with said modulating system for causing variations of impedance of a conductive part thereof, an oscillating circuit for said second system, and means for controlling the constants of said oscillating 105 circuit.
17. An electron discharge system having a control element, a second electron discharge system, and means whereby said control element is maintained at a suitable average working potential by said second system; said means including an input path for said first-mentioned system; said input path including at least a portion of a leak path of said second system, a shunt path to said portion, and means for reducing the reaction of said first system on said second system due to varying potential differences across said shunt path.
18. A system comprising an electron discharge oscillator, means including an electron discharge device having an impedance varying element and a cathode for causing said oscillator to produce modulated waves, and means including conductive connections 125 130

- between said device and said oscillator whereby said impedance varying element is maintained at a desired average working potential with respect to said cathode.
- 5 19. The combination in an electrical circuit of means for producing a high impedance at a relatively low range of frequencies and a high impedance at a relatively high range of frequencies comprising a highly inductive choke coil having a large number of turns and a large inherent and undesired distributed capacity between said turns with an inductance coil of small distributed capacity to more than compensate for the capacity reactance of said choke coil at high frequencies and thereby produce the desired impedance at the high range of frequencies.
- 10 20. In a signal transmission system the combination of a source of low frequency variations, a source of high frequency variations, and means to impress said low frequency variations upon said high frequency source without impressing said high frequency variations upon said low frequency source comprising a highly inductive low frequency choke coil in shunt with said high frequency source as viewed from said low frequency source, and a high frequency choke coil in series with said low frequency source as viewed from said high frequency source.
- 15 21. In combination, an electrical system including a discharge device and means to vary the impedance thereof at a relatively low frequency rate, a second discharge device and means to vary the impedance thereof at a relatively high frequency rate, a low frequency choke coil in parallel with said second device as viewed from said first device, and a high frequency choke coil to counteract the effect of the distributed capacity of said low frequency choke coil located in series with said low frequency choke coil as viewed from said second discharge device.
- 20 22. A modulating system comprising a variable impedance, a source of constant current supply, a high frequency generator in parallel with said impedance with respect to said source of supply, means for varying the impedance of said impedance device at signal frequencies, a shunt path around said generator comprising means whereby the impedance of said path for currents of the signal frequencies is rendered large compared to the impedance of said generator.
- 25 23. A modulating system comprising a variable impedance, a source of constant current supply, a high frequency generator in parallel with said impedance as viewed from said source, means for varying the impedance of said impedance device at a plurality of signaling frequencies, and a shunt path around said generator comprising means whereby the impedance of said path
- is rendered negligibly different for currents of the various signaling frequencies.
24. A circuit including three vacuum tube systems, each system having a grid circuit and a plate circuit, connections between the grid circuit of the first system and the grid circuit of the second system whereby the first acts upon the second, and connections between the plate circuit of the second and the plate circuit of the third whereby the second acts upon the third, said connections including an impedance element across which differences of potential are produced by the second mentioned system and impressed upon the plate circuit of the third mentioned system.
- 25 25. A transmitting circuit comprising three vacuum tube systems, a cathode, an anode and a control element for each system, a grid-to-grid and cathode-to-cathode connection between the first and the second system for supplying from said first to said second system, an anode-to-anode and cathode-to-cathode connection between the second and third systems, and a shunt path containing an impedance element connected across said last mentioned connections.
- 30 26. A discharge device for generating oscillations having an anode, a cathode and an impedance control element, a second discharge device connected thereto by means whereby it varies a generating characteristic of said first mentioned device and including an anode, a cathode and an impedance control element, and a common means for applying to each control element an average potential different from the potential of the associated cathode.
- 35 27. A discharge device for generating oscillations having an anode, a cathode and an impedance control element, a discharge device for varying a generating characteristic of said first mentioned device including an anode, a cathode and an impedance control element, a leak path between the control element and the cathode of said first mentioned device, and means for applying between the control element and the cathode of the second mentioned device a portion of the potential difference across said leak path.
- 40 28. In an electrical system, a series arrangement of elements for producing relatively high impedance at a low range of frequencies and relatively high impedance at a high range of frequencies comprising an inductive winding having high impedance to low frequencies but low impedance to higher frequencies due to capacity effect, and an inductive winding in series circuit relation to said first-mentioned winding and having small capacity effect at said high frequencies.
- 45 29. In an electrical system, an inductive winding having high impedance to low frequencies but low impedance to higher frequencies.

- 1 frequencies due to capacity effect, and means 5 for causing a series circuit including said winding to have high inductive reactance to both high and low frequencies without 10 causing the impedance to direct current and low frequencies to be substantially greater than the impedance of said winding comprising an inductive winding in series circuit relation with said first mentioned winding, said last named winding having small capacity effects and high impedance at said high frequencies and negligible impedance to said lower frequencies and to direct current.
- 15 30. A source of modulating waves, means including a modulating device for producing carrier waves modulated by waves from said source, circuit connections between said devices, and an impedance element of relatively low impedance to said modulating waves but of relatively high impedance to said carrier waves to prevent the passage of currents of the carrier wave frequency through said connections to said source.
- 20 31. A source of modulating waves comprising a thermionic device and means for varying its impedance at a modulating wave frequency, means including a second thermionic modulating device for producing carrier waves modulated by waves from said source, circuit connections between said devices, and an impedance element of relatively low impedance to said modulating waves but of relatively high impedance to said carrier waves to prevent the passage of currents of the carrier wave frequency through said source of modulating waves.
- 25 32. In combination, a plurality of connected systems, one of said systems including a device for producing modulated carrier frequency waves and the other of said systems being a discharge device including an anode, a cathode and a control element, means for varying the impedance of the discharge device at a frequency lower than the carrier frequency, and means for preventing currents of the carrier frequency from being impressed on said discharge device while allowing currents of said lower frequency to be impressed from said discharge device 5 upon said device for producing modulated waves.
33. In a high frequency system, a space discharge device having an anode, a cathode and a control element, means for varying 55 the impedance of said device at a carrier frequency, a second space discharge device having an anode, a cathode, and a control element, means for varying the impedance of said second device at a modulating frequency, 60 a source of current for supplying said devices, means for maintaining the sum of the supplied currents constant as regards modulating frequency variations, and a common means for heating both of said 65 cathodes.
34. A high frequency signalling system provided with an electron discharge device having a cathode, an anode and a grid and having plate and grid circuits coupled together to produce radio frequency oscillations, a second electron discharge device having a cathode, an anode and a grid for producing an audio frequency potential variation in the plate circuit of the first device 70 and means for impressing a radio frequency current from the first device upon the grid circuit of the second device to maintain a negative potential upon the grid of the second device.
35. A high frequency signalling system provided with an electron discharge device having a cathode and anode and a grid, and having plate and grid circuits coupled together to produce radio frequency oscillations, a second electron discharge device having a cathode, an anode and a grid and a grid circuit for producing an audio frequency potential variation in the plate circuit of the first device, and a condenser 85 shunted by a resistance forming a part of the grid circuit of the first device, a part at least of said resistance being included in the grid circuit of the second device.
- In witness whereof, I hereunto subscribe 90 my name this 9th day of April A. D., 1918.
- RAYMOND A. HEISING.
